UNITED STATES PATENT OFFICE.

ISAAC F. WILLEY, OF PHILADELPHIA, PENNSYLVANIA.

IRONING-MACHINE.

1,252,213.

Specification of Letters Patent.

Patented Jan. 1, 1918.

Application filed September 30, 1913. Serial No. 792,550.

To all whom it may concern:

Be it known that I, ISAAC F. WILLEY, a citizen of the United States, residing in the city and county of Philadelphia, State of Pennsylvania, have invented a new and useful Ironing-Machine, of which the following is a specification.

My invention relates to a novel construction of an ironing machine, which is especially adapted to have the collars, or similar articles which are ironed, to be fed into the machine laterally, and wherein I provide a novel construction of floating bearings for certain of the ironing rollers, said bearing being guided or slidingly mounted in a suitable portion of the frame work of the machine, and having secured to or projecting from their upper surfaces, a pneumatic cushioning device, provided with means for the introduction of fluid pressure above and below the piston thereof, whereby the requisite yielding pressure may be exerted at all times upon said floating bearings and the rollers journaled therein, whereby I am enabled to attain better results than heretofore, since the ironing rollers are caused to engage the articles to be ironed with only the necessary or requisite pressure to produce the desired finish, which cannot be accomplished in ironing machines of the conventional type, wherein the ironing rollers are mounted in fixed bearings or bearings actuated by springs.

To the above ends, my invention consists of a novel construction of ironing machine having the bearings for the ironing rollers yieldingly supported upon a cushion of air or other fluid pressure, which can be increased, diminished or otherwise regulated, according to requirements.

It further consists of other novel features of construction, all as will be hereinafter fully set forth.

For the purpose of illustrating my invention, I have shown in the accompanying drawings, one form thereof which is at present preferred by me, since the same has been found in practice to give satisfactory and reliable results, although it is to be understood that the various instrumentalities of which my invention consists can be variously arranged and organized, and that my invention is not limited to the precise arrangement and organization of these instrumentalities, as herein shown and described.

Figure 1 represents a side elevation of an ironing machine embodying my invention.

Fig. 2 represents a front elevation of the machine.

Fig. 3 represents a side elevation, partly in section, of certain of the parts seen in Fig. 1, on an enlarged scale.

Fig. 4 is a section on line 4—4 of Fig. 1.

Fig. 5 is a perspective view of the feeding mechanism.

Fig. 6 is a diagrammatic view showing the arrangement of the cylinders.

Similar numerals of reference indicate corresponding parts in the figures.

Referring to the drawings:

1 designates the frame of my novel ironing machine, in which is journaled the main driving shaft 2, provided with a tight and a loose pulley 3 and 4 respectively, and pinion 5. The pinion 5 meshes with a gear wheel 6, fast on a shaft 7 journaled in the frame 1, said shaft 7 having fast thereon a pinion 8 and sprocket wheels 9 and 10. The sprocket wheel 9 imparts motion through a chain 11, to a sprocket wheel 12, fast on a shaft 13, journaled in the frame 1. The shaft 13 has fast thereon the sprocket wheels 14 and 15, as seen in Fig. 4, for engagement with the sprocket chains 16 and 17, respectively, whereupon a rotary motion may be imparted to the padded rollers 18 of relatively small diameter, that are journaled in groups in the floating boxes or bearings 19, as will be understood from the right portion of Fig. 3 and from Fig. 4.

The bearings 19 are each provided with a stem 20, which is adjustably fitted in an opening 21, in the frame 1, so that said bearings may be properly guided in their movements toward and away from the drum 22 journaled in the frame 1.

Each journal bearing 19 has swiveled or otherwise connected thereto, as at 23, a piston rod 24, provided with a head 25, having a sliding fit within a cylinder 26. The cylinders 26 are secured to brackets 27, which latter are fastened to the frame 1 and also serve as guards for the sprocket wheels 14 and 15 and chains 16 and 17. The cylinders 26 are each provided with ports 28 and 29 for the admission of compressed air or other motive fluid, so as to operate or control the operation of the piston head 25 and its adjuncts. The pinion 8 engages a gear wheel 30 fast on the tubular shaft 31, journaled in

the frame 1, and which has secured thereto the drum 22. The sprocket wheel 10 imparts motion to a chain 32, that is in engagement with a sprocket wheel 33, so as to rotate the latter, and consequently the shaft 34 and hollow roller 35 fast thereon.

The shaft 34 has fast thereon a gear wheel 36 that meshes with a gear wheel 37 fast on the shaft 38, to which is secured the feed 10 roller 39. The shaft 38 is journaled in the heads 40, from which depend piston rods 41, whose heads 42 are fitted within the cylinders 43, secured to the frame 1. The cylinders 43 are provided with ports 44 and 45 15 for admission of compressed air or other motive fluid so as to move the roller 39 toward and away from the roller 35, as will be understood from Figs. 3 and 5.

Interposed between the roller 39 and adjacent roller 18 is an inclined table or ledge 46, see Fig. 3, adjustably fitted in the frame 1, so that the position of said table 46 may be varied with respect to the rollers 18 and 39, according to requirements. I have shown 20 one form of such adjustment in Fig. 3, the operation of which will be apparent.

Secured in the frame 1, is a rod 47 that serves as a guard to prevent an operator's hands from reaching the feed rollers 35 30 and 39. The frame 1 has secured thereto a receptacle 48 for the collars 49 or other articles to be ironed, and also with a receptacle 50 for the ironed articles.

It will be seen on referring to the diagrammatic view in Fig. 6, that the cylinders 25 are in communication with an air compressor 51, through the pipes 52 and 53, and that the two latter lead to a three-way 35 valve 54 that is connected to a pipe 55, leading from the air compressor 51. I deem it unnecessary to show or describe the three-way valve in detail, as any conventional type of valve may be employed, according 40 to requirements, and such valve may be located at any point in the piping system, which will be convenient to the operator.

The operation of the machine is as follows:—

Assuming that steam or other suitable 50 heating medium is introduced into the drum 22 and roller 35, by any suitable means, and that the machine is set in motion, by the rotation of the gears and other power transmission devices, the operator places a collar 55 or other article to be ironed upon the receptacle 48, as seen in Fig. 5, and feeds said collar 49, preferably laterally, as shown, to the rollers 35 and 39, so that the collar is drawn between said rollers, whereupon the 60 first step in the process of ironing takes place. The collar 49 then slides or travels down the inclined table or ledge 46, seen in Fig. 3, and is directed thereby to the drum 22 and the foremost roller 18 in the 65 series of rollers 18, whereupon said collar is

drawn between the drum 22 and series of rollers 18, and after leaving the last roller 18, it drops into the receptacle 50, from which it and other collars or articles, as ironed, may be taken to any desired point. 70

When the handle of the three-way valve 54 is in the position seen in Fig. 6, compressed air flows from the compressor 51 through the pipes 55, valve 54 and pipes 52 into the upper portion of each cylinder 26, thereby causing the piston head 25 thereon and its adjuncts to lower, whereupon the rollers 18 are caused to bear against a collar 49, with a proper degree of pressure, and which may be regulated or increased or diminished, according to requirements, and is regulated by adjusting the valve 54. 75

When the heads 25 in the cylinders 26 are moving toward the drum 22, the air on the opposite side of said heads 25 escape from the cylinder 26, through the pipes 53 and are directed by the latter to an exhaust port, not shown but of conventional construction, in the valve 54. 80

When the handle of the valve 54 is turned 90 to the right from its position seen in Fig. 6, the flow of air from the compressor 51 will pass through the pipes 55 and 53 to the underside of the piston heads 25, and thus cause the rollers 18 to move away from the 95 drum 22, in which case the pipes 52 now become exhaust pipes and direct the air to the usual exhaust port, not shown, in the valve 54, or, in other words, the flow of air is in a direction opposite to that indicated by the 100 arrows in Fig. 6, with the exception of the arrow that indicates the flow of air in the pipe 55.

It will therefore be seen from the foregoing that by the employment of the feed 105 roller 39, having the pneumatic pressure regulating device, the desired pressure can be readily attained with respect to the feed roller 39 by the proper manipulation of the three-way valve or cock 54. By arranging 110 the ironing rollers 18 in groups of threes, which can be increased or diminished, according to requirements, in their floating bearings and by employing the fluid pressure regulating devices in connection therewith, 115 I am enabled to get the desired or requisite pressure upon the articles which are being ironed, around the principal operative surface of the drum 22. By the employment of the piston rods 24 having the interlocking 120 heads thereon, and by making the cylinders 26 detachable from the brackets 27, I am enabled to readily assemble the principal operative mechanisms in a convenient and expeditious manner, and the ironing rollers 18 125 and their adjuncts, as well as the operating mechanism therefor are readily accessible at all times for the purpose of inspection, replacement or repairs.

It will of course be understood that the 130

source of fluid pressure supply, as the compressed air tank 51 may be arranged at any convenient point with respect to the machine, and that the three-way cock or valve 54 may be located at any desired point so as to be manually actuated by the operator, when desired. The arrangement of the various operative parts is such that any desired element can be readily disconnected, the machine can be readily taken apart or dismantled, or any desired element thereof readily made accessible at any time for the purpose of inspection or repairs.

It will now be apparent that I have devised a novel and useful construction of an ironing machine, which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In an ironing machine, the combination of frame sides having radially-disposed openings, a drum mounted to turn between the frame sides, brackets fixed to the frame sides, journal-bearings movable radially within said brackets and having inwardly extending stems disposed and movable radially in said openings in the frame sides, a transverse roller journaled in and extending between said bearings and opposed to the periphery of the drum, cylinders carried by the brackets and extending radially outward therefrom, pistons movable in said cylinders and having rods connected with the journal bearings, and means for supply-

ing fluid under pressure to and exhausting the same from the cylinders at opposite sides of the pistons.

2. In an ironing machine, the combination of frame sides having radially-disposed openings, a drum mounted to turn between the frame sides, brackets fixed to the frame sides, stems disposed and movable radially in said openings in the frame sides, journal bearings fixed to and extending in opposite directions from the outer ends of the stems and substantially parallel to the periphery of the drum, transverse rollers journaled in and extending between said bearings, cylinders carried by the brackets and extending radially outward therefrom, pistons movable in said cylinders and having rods connected with the central portions of the journal bearings, and means for supplying fluid under pressure to and exhausting the same from the cylinders at opposite sides of the pistons.

3. The combination in an ironing machine, of frame sides having radially-disposed openings, radially-disposed cylinders fixed with respect to the frame sides and spaced outwardly beyond the outer ends of said openings and arranged in radial alignment therewith, journal bearings movable radially between the outer ends of said openings and the inner ends of said cylinders and having inwardly extending stems movable radially in the openings, a drum mounted to turn between the frame sides, a transverse roller opposed to the periphery of the drum and journaled in said bearings, pistons movable in the cylinders and having rods connected with the journal bearings, and means for supplying fluid under pressure to and exhausting the same from the cylinders at opposite sides of the pistons.

ISAAC F. WILLEY.
